UNITED STATES PATENT OFFICE.

THOMAS L. TALIAFERRO, OF CHICAGO, ILLINOIS.

JAR-CLOSING MACHINE.

Application filed December 1, 1923. Serial No. 678,032.

The invention relates to new and useful improvements in jar closing machines, and more particularly a jar closing machine wherein the jars pass continuously and in succession through the machine, and wherein the securing means operates to secure a metal cap to a jar without stopping the movement of the jar. By the term "cap" is included jar bands and other forms of closures having a depending flange.

An object of the invention is to provide a machine of the above type wherein the flange of the metal cap is turned underneath a ledge at the mouth of the jar by means of a stationary member with which the cap makes rolling contact, and wherein the initial inturning of the lower edge of the flange is accomplished by positive means while the final inturning of the flange and the sealing of the cap on the jar is accomplished by yielding means.

A further object of the invention is to provide a machine of the above type with traveling means for holding the cap in contact with the member which re-shapes the flange, which traveling means is formed so as to yield under excessive pressure.

A still further object of the invention is to provide a machine of the above type which is so constructed that the jar is supported by the ledge at the mouth of the jar during the sealing of the jar cap to the jar.

A further object of the invention is to provide a machine of the above type with means located at the entrance end of the machine for insuring the preliminary seating of the metal cap on the jar as it enters the jar closing machine.

A further object of the invention is to provide a machine of the above type which may be readily adjusted for jars of different heights, and caps of different diameters.

In the drawings which show by way of illustration one embodiment of the invention—

Figure 1 is a side view of a machine embodying my improvements;

Fig. 2 is a plan view of the same;

Fig. 3 is an end view of the machine;

Fig. 4 is a view in plan of a portion of the machine intermediate its ends and showing the indicating means for indicating the size of jar cap for which the machine is set;

Fig. 5 is a sectional view on the line 5—5 of Fig. 4;

Fig. 6 is a side view of a portion of the flange supporting and turning member;

Fig. 7 is a sectional view on the line 7—7 of Fig. 6;

Fig. 8 is an enlarged view in section, 60 showing the closing means and conveying means operating upon the jar to form the initial inturning of the flange of the cap;

Fig. 9 is a similar view showing the finishing of the inturning of the flange of the cap 65 and the sealing of the same to the jar;

Fig. 10 is a plan view of the frame which supports the closing means and the conveying means;

Fig. 11 is a side view of the frame shown 70 in Fig. 10;

Fig. 12 is a detail, showing in face view the closing means which turns the flange on the cap underneath the ledge at the mouth 75 of the jar.

The machine embodying the present invention is an improvement upon the jar closing machine shown in my prior Patent No. 1,495,650, dated May 27, 1924.

The machine is especially adapted for 80 attaching metal caps, such as a metal jar band cap, to the mouth of a glass jar. The jar has a ledge at its mouth and the cap is secured thereto by turning the lower portion of the flange on the cap underneath the 85 ledge. The jars with the caps loosely resting thereon are brought to the machine by an endless conveyor. Just before the jars enter the machine a traveling pressure means engages the jar cap and insures that 90 the cap is properly seated on the jar. The machine includes two parallel spaced members, one of which is stationary, while the other is movable. The movable means 95 operates to convey the jar through the machine and to roll the cap flange along the stationary member. The stationary member is so constructed as to turn the flange of the cap underneath the ledge on the jar.

The stationary member and the movable 100 member are further so constructed as to support the jar from the ledge at the mouth of the jar. The stationary member at its entrance end has co-operating members held in fixed relation to each other which operate 105 to inturn the flange of the cap underneath the ledge on the cap to a certain extent. The face of this member which engages the lower edge of the flange is provided with 110 transverse ribs which operate to corrugate

or break the extreme edge of the flange to assist in the inturning of the flange underneath the ledge. The remainder of the stationary closing means has co-operating parts 5 which yield relative to each other and these complete the inturning of the flange underneath the ledge on the jar. Inasmuch as they yield any liability of crushing the jar at the ledge is avoided. The movable member 10 travels along a bar which is yieldingly mounted so that the movable member gives or moves laterally relative to the stationary member and avoids the excessive pressure which, in a direction diametrically across 15 the mouth of the jar, might result in the crushing of the jar.

Referring more in detail to the drawings, my improved machine includes a supporting base 1, carrying a standard 2, on which the 20 main frame structure 3 of the machine is mounted. Secured to this main frame structure are side frames 4 and 5. Carried by said side frames, at one end of the machine, is a pulley 6. At the other end of 25 the side frames is a pulley 7. The endless conveyor belt 8 runs over these pulleys 6 and 7. Mounted in the main frame 3 is a main shaft 9, carrying a gear wheel 10, which meshes with a gear wheel carried by the 30 armature shaft of the motor 11. It will be understood, of course, that the main shaft may be driven in any suitable way, but I prefer the above means, as I am able thereby to provide a self-contained machine.

35 On the shaft 9 is a beveled gear 13. A shaft 14 extends lengthwise of the machine and carries a gear 12 which meshes with a gear 13. This shaft 14 carries a beveled gear 15 at its other end, which in turn 40 meshes with a beveled gear 16, carried by a vertical shaft 17. The vertical shaft 17 carries a spiral gear 18 which meshes with a gear 19 on a cross shaft 20. This cross shaft 20 carries a sprocket wheel over which a 45 sprocket chain 21 runs, and this sprocket chain 21 in turn runs over a sprocket wheel 22 carried by the shaft 23 on which the pulley 7 is mounted. Thus it is that the 50 pulley 7 is positively driven from the motor and this drives the endless conveyor.

The jars enter from the left-hand end of the machine, as viewed in Fig. 1. They are fed on to the conveyor belt and are conveyed by said conveyor belt into the machine. 55 Suitable guide rails 24 guide the jar as it enters the machine. The jars to be closed are provided with a ledge at their upper ends, of the well-known character, and the metal cap has a flange which is adapted to be turned underneath said ledge.

In Fig. 8 of the drawings, I have shown a jar indicated at J, with a metal cap C resting lightly thereon. Said jar has a ledge j underneath which the lower portion e of the 60 flange of the metal cap is adapted to be

turned for securing the cap to the jar. It is essential that the cap shall be seated on the jar before it enters the closing mechanism of my machine. In order that this may be insured, I have provided a traveling pressure means underneath which the jars pass. Said pressure means consists of a traveling belt 25, running over pulleys 26 and 27. These pulleys are mounted on a frame 28 which is pivoted at 29 to the frame 70 of the machine. A rod 30 extends through a bracket arm 31, also mounted on the frame of the machine and this rod has a ball head connection with the frame 28 supporting the pressure means. A spring 32 surrounds this rod 30 and bears at one end against the bracket 31 and at its other end against a nut 33 on the rod. This spring normally presses the rod downwardly and thus holds the traveling belt 25 in contact with the jars 75 passing beneath the same. The entire frame 28 can yield bodily compressing the spring 32. The downward movement of this pressure device is limited by means of nuts 34.

80 Mounted in the side frames 4 and 5 is a shaft 35. This shaft 35 carries a sprocket wheel which is driven by a sprocket chain 36. This sprocket chain 36 runs over a sprocket wheel on the shaft 20. A belt tightener 37 is provided for the sprocket 85 chain 36 to take up the slack therein as the belt is of considerable length and this belt tightener serves as a means for holding the chain from contact with the frame and insures the free running of the chain. A 90 beveled gear on the shaft 35 meshes with a beveled gear 38 carried by a vertical shaft 39, and this shaft 39 in turn carries a beveled gear 40 which meshes with a beveled gear on the shaft 41 which carries the pulley 95 27. Thus it is that the pulley 27 is positively driven and this drives the traveling belt 25. A plate 42 carried by the frame 28 backs up the portion of the belt between the pulleys. The belt travels over this plate 100 and the plate prevents the belt from yielding except as the entire frame yields.

105 It will be readily seen from the above that as the jar passes underneath this pressure means the metal cap will be pressed down onto the jar and fully seated thereon. The jars, of course, are supported and carried along by the conveyor belt 8 at this time.

Rising from the main frame members are 110 four posts 43. Two of these posts are located adjacent the entrance end of the machine and the other two at the delivery end of the machine. There is a yoke 44 for each pair of posts which extends across the 115 machine. Mounted to slide freely on each pair of posts is a cross head 45. A rod 46 is secured to the cross head 45 and this rod passes up through the yoke member 44. The rod 46 is threaded throughout a por- 120

tion of its length and mounted on said threaded portion of the rod is a sleeve 47 carrying a hand wheel 48, by means of which the sleeve can be turned. This sleeve rests 5 on the upper face of the yoke 44. When the sleeve is rotated in one direction the rod 46 will be raised and when rotated in the other direction, said rod will be lowered. This serves as a means for raising and lowering 10 the cross heads 45 and thus setting the machine for different heights of jars.

Also mounted on the sleeve 47 is a sprocket wheel 49. There is a sprocket wheel at each 15 end of the machine and a sprocket chain 50 runs over these sprocket wheels, so that when one sleeve is turned the other sleeve will be likewise turned in the same direction and to the same extent. The operator can, therefore, by turning one of the hand 20 wheels, raise both cross heads. A shield or casing 49 covers the sprocket chain 50.

Extending from one cross head to the other and formed integral therewith are side members 51. These side members are 25 connected by a series of cross bars 52 which are formed integrally with the side members and also by end members 53, which are likewise integral with the side members. These side members 51, together with the 30 cross bars 52 and the cross heads 45 form a frame structure on which the devices for closing the jar are carried. It is on this frame structure also that the pressure mechanism referred to above is mounted. 35 When the hand wheels 48 are turned this entire frame structure together with the pressure means is raised or lowered.

Extending along one side of the machine 40 is a rail 54 which carries the means for turning the flange of the jar cap underneath the ledge on the jar. This rail is supported by the frame structure just described. Bolts 45 pass through slots 56 in the cross bars 52 and are threaded into the rail. These 50 slots are elongated, as clearly shown in Fig. 2, and are so made for the purpose of permitting the rail 54 to be bodily shifted toward and from the center of the machine, as will be hereinafter more fully described.

This supporting rail 54 is provided with 55 an L-shaped plate 57 which extends throughout the entire length of the machine, and is positioned so that the horizontal portion overhangs the vertical portion. The extreme inner edge of this plate is beveled at 58, see Fig. 7. Co-operating with the L-shaped plate 57 are a series of plates 60 which operate to turn the flange of the jar cap underneath the ledge at the mouth of 60 the jar. At the entrance end these plates are constructed as shown at the left-hand end of Fig. 10 and in section in Fig. 7. Said plates have their extreme forward sides beveled off at an angle, as indicated at 65 (see Fig. 7). There are a series of these

plates 60, as indicated in Fig. 12. These plates are secured to the supporting rail 54 by means of screw bolts 61. The beveled face 59 is provided with a series of ribs and grooves, and this beveled face is set so that its upper edge is just inside the vertical wall 62 of the plate 57 (see Fig. 7). As clearly shown in Fig. 8, the cap C enters this recess between the plates 57 and 60 and the extreme lower edge c will make contact with the beveled or ribbed face 59 of the plate. The operation of these plates upon the cap will be referred to more in detail later.

The cap is rolled along the rail 54. The remainder of the structure for turning the edge of the cap underneath the ledge on the jar is formed by means of plates 62. These plates 62 are provided with a horizontal ledge 63 and a vertical wall 64 which extends upwardly from said ledge. This wall 64 is in alinement with the wall 62 on the plate 57 directly above the same. There are a series also of these plates 62 and they are independently mounted on bolts 65. Preferably, there are two bolts 65 for each plate. These bolts are threaded into the rail 54. A spring 66 on each bolt is seated in a recess 67 in the underface of the plate 62 and rests at its lower end on a nut 68 threaded onto the bolt 65. Thus 65 it is that the springs normally hold these plates 62 pressed upwardly and seated against the plate 57 directly above the same. The springs will yield to permit the plate 62 to move downwardly. By adjusting the 100 nuts 68 the tension of the spring on this plate 62 can be varied. The horizontal ledge 63 is curved at its entrance end at 69 in a downward direction, so as to make an open mouth recess to receive the flange 105 of the cap on the jar. The ledge 63 is also curved downwardly at 70, at the delivery end of the rail so as to permit the jar to come down on to the conveyor belt, said jar being supported by the ledge at 70 the mouth of the jar, while it is rolling along the rail 54.

The jar is rolled along said rail 54 by means of plates 71 and 72 which are connected to form an endless chain. The two 115 plates 71 and 72 are spaced by means of a spacer block 73, and these plates which are arranged in pairs are connected by means of links 74, one above and one below each pair of links. Pivot bolts 75 pass through the links and plates and thus form the endless chain. At the receiving end of the machine there is a sprocket wheel 76 over which this sprocket chain runs and at the delivery end of the machine there is another 120 sprocket wheel 77 over which said sprocket chain likewise runs. The sprocket wheel 76 is mounted in a bearing 78 which is capable of being adjusted by adjusting bolts 79 of the usual character for taking up the 130

slack in the sprocket chain, as this sprocket chain must run under fairly tight conditions. The end of the side member 51 is forked to permit the adjustment of the sprocket wheel 76. The shaft 80 supporting the sprocket wheel 77 is mounted in the other end of the side member 51.

Extending along the other side of the machine from the rail 54 is a second rail 81. This rail 81 is carried by projecting rods 82 which are inserted in openings in the side frame 51 and are adjustably secured therein by set screws 83. The guide rail 81 has an upper inwardly projecting member 84 and a lower inwardly projecting member 85, which are spaced from each other. Said lower member carries a hardened plate 86 and the plates 71 and 72 travel between this hardened plate 86 and the overhanging member 84. The pivot pins connecting the plates to form the endless chain ride along this hardened plate 86 and this insures that the plates 71 and 72 will move in a horizontal line.

Located in rear of the conveyor chain formed by these plates and links is a bar 87. Said bar is carried by bolts 88, which extend through openings in the rail 81 and springs 89 between this bar 87 and the rail normally press the bar 87 outwardly. Said bar is formed with a projecting ledge 90 which extends between the plates 71 and 72 and further aids in holding the chain conveyor so that it will travel in a horizontal line. Nuts 91 threaded on the bolts 80 limit the outward movement of the bar 87. The inner upper face of the plate 72 is beveled, as clearly shown in Fig. 5 of the drawings, and the lower inner face of the plate 71 is likewise beveled. The metal cap which is shown in dotted lines in Fig. 5 lies between these beveled faces and is engaged thereby.

At the delivery end of the machine there is a vertical shaft 92 which carries a beveled gear 93 at its lower end meshing in turn with a beveled gear 94 on the shaft 20. This shaft 92 extends through the sprocket wheel and said sprocket wheel 77 is splined thereto so that the rotations of the shaft will impart rotations thereto. The reason that the sprocket wheel is splined to this shaft is that the sprocket wheel and the mechanism associated therewith are mounted in bearings carried by the side rail 51 and are vertically adjustable therewith so as to set the machine for different heights of jars. Said side rail has projecting brackets 95 which serve as a bearing support for the sprocket wheel 77. At the other end of the machine there are brackets 96, carried by the side rail which support the sprocket wheel 76.

There is a housing or guard rail 97 which extends about this traveling chain except

where the chain is running in the recess formed in the rail 81.

As has already been stated, the jars are placed on the endless conveyor which carries the jar underneath the pressure means and after they leave the pressure means, then the jar cap passes into the recesses between the plates 57 and 60 on the one side of the machine and the recess between the plates 71 and 72 on the other side of the machine. The distance between these plates at the opposite sides of the machine is such that the jar cap will be forced into the recesses between the plates 57 and 60, bringing the lower edge of the cap into contact with the beveled face 59 of the plates 60. This beveled face 59 which is ribbed will operate to break or corrugate the lower edge of the flange of the metal cap and start the turning of the same underneath the ledge 85 on the bottle. As soon as this lower edge of the flange is bent by means of this beveled edge the spring pressure operating upon the plates 71 and 72 will crowd the jar back and

up into the recess, and the jar will be lifted from the endless conveyor and supported in the remainder of its travel through the machine by said ledge at the mouth of the jar. As the jar rolls along the rail 57 the flange will be turned to a greater extent underneath the ledge and the jar and cap brought up into the recess, as clearly shown in Fig. 9 of the drawings. After the flange is well turned underneath the ledge then the cap and jar will pass onto the section of the rail 62 having the horizontal face. These yielding plates 62 will turn the flange to substantially horizontal position underneath the ledge. Said plates will yield to any excessive pressure caused by unevenness in the thickness of the metal or the glass forming the ledge at the mouth of the jar and will prevent said jar from being crushed.

Furthermore, inasmuch as the jar is lifted from the conveyor belt and the pressure which turns the metal cap underneath the ledge is all applied directly at the mouth of the jar by the yielding pressure of the plates 62, it will be seen that there is no danger of crushing the jar by reason of the fact that the jars vary in height and a jar of more than the average height passes through the machine. The jars when they leave the plates 62 will pass down the curved ledge 70 and be gradually lowered on to the conveyor belt which will convey them out of the machine. The travelling chain which conveys the jar through the machine and causes it to turn or roll along the closing rail can likewise yield to extreme diameters of jars and this prevents any liability of creating a pressure diametrically of the mouth of the jar which is likely to crush the same.

Said guide rail is provided with lugs 100. 130

Adjusting bolts 101 are secured to these lugs so that said bolts may be turned, but they cannot move endwise in the lugs. Said bolts are carried by threaded projecting sleeves 102 formed as a part of the side rail of the machine. By turning these adjusting bolts 101 after the bolts 55 have been loosened, the upper guide rail may be adjusted toward or away from the center of the machine and thus set to accommodate jars of different diameters. The entire frame can be raised and lowered by the hand wheels 48 and thus take care of jars of different heights, as has already been stated.

At the delivery end of the machine there is a disk 103 which disk overlies the conveyor belt and is adapted to receive the jars from the conveyor belt. Said disk is carried by a shaft 105, mounted in a suitable bearing 106 on the main frame. This shaft carries a beveled gear 107 which meshes with a beveled gear 108^a on the shaft 23 which carries the pulley 7. By this mechanism the disk is rotated. The edge of the disk is beveled so that the jars may be readily forced up onto the disk by the conveyor. A guide rail 108 mounted at 109 on the main frame extends over the conveyor belt and the rotating disk and directs the jars onto the disk. A radial guide rail 110 extends to the outer edge of the disk 103 and operates to strip the jars from the disk. In order to determine the setting of the machine for different size caps, I have provided gage plates 111, carried by the upper frame structure and the adjustable rail is provided with a pointer 112. This gage plate has a gage formed thereon and the finger co-operating therewith will indicate the size of the cap for which the machine is set. This gage is in millimeters as caps are usually referred to by their diameter in millimeters.

It is thought that the operation of the machine will be obvious from the detail description given above. The jars with the caps lightly resting thereon are placed on the conveyor belt and are conveyed thereby underneath the pressure mechanism which seats the cap on the jar. The caps then pass in between the spaced rails along the sides of the machine, one of which carries the traveling links and the other of which carries the plates for turning the metal underneath the ledge on the jar. As has been described the lower edge of the metal cap is first more or less broken or corrugated by the ribs on the rail forming a part of the closing means, and the edge of the flange turned underneath the ledge at the mouth of the jar. The jar is supported by the closing means on the one side and the traveling chain on the other side and as the jar passes through the machine it will be turned or rolled along the closing rail, the flange of the cap turned further and further

under the ledge and finally the yielding pressure means will force the underturned part up against the lower portion of the ledge and thus tightly seal the metal cap to the jar.

It will be noted that the rails for turning the flange underneath the ledge on the cap which yield are made to yield in independent sections so that the jars may be fed through the machine closely following each other and if one rail yields, because of extra thickness of the metal on the ledge at the mouth of the jar, the next following jar will be properly closed as it is only the plate which engages the cap and ledge that will be moved.

It sometimes occurs that the spilled contents of a jar or broken jar will stick to the conveyor belt 8, which would cause trouble when another jar enters resting on the same. In order to avoid this, I have provided a scraper S, carried by a yielding arm A, which presses against the lower face of the traveling conveyor belt and scrapes off any accumulation thereon.

It is obvious that minor changes in the details of construction may be made without departing from the spirit of the invention as set forth in the appended claims.

Having thus described the invention, what I claim as new and desire to secure by Letters Patent, is—

1. A jar closing machine having in combination, means for turning the flange of the jar cap underneath the ledge on the jar, means for conveying the jar with the cap resting thereon through the machine with the cap in rolling contact with the flange turning means, said flange turning means including spaced devices between which the flanged edge of the cap passes for positively starting the inturning of the flange on the cap, and spaced devices for finishing the inturning of the flange underneath the ledge of the jar, and thus sealing the cap on the jar, said last-named devices being mounted so as to yield relative to each other.

2. A jar closing machine having in combination, means for turning the flange of the jar cap underneath the ledge on the jar, means for conveying the jar with the cap resting thereon through the machine with the cap in rolling contact with the flange turning means, said flange turning means including spaced devices between which the flanged edge of the cap passes for positively starting the inturning of the flange on the cap, and spaced devices for finishing the inturning of the flange underneath the ledge of the jar, and thus sealing the cap on the jar, said last-named devices being mounted so as to yield relative to each other, said conveying means including a series of spaced plates connected to form an endless chain, the adjacent faces of the plate being beveled

for engagement with the cap at the upper and lower portions of the flange thereon.

3. A jar closing machine having in combination, means for turning the flange of the jar cap underneath the ledge on the jar, means for conveying the jar with the cap resting thereon through the machine with the cap in rolling contact with the flange turning means, said flange turning means including spaced devices between which the flanged edge of the cap passes for positively starting the inturning of the flange on the cap, spaced devices for finishing the inturning of the flange underneath the ledge of the jar, and thus sealing the cap on the jar, said last-named devices being mounted so as to yield relative to each other, said conveying means including a series of spaced plates connected to form an endless chain, the adjacent faces of the plate being beveled for engagement with the cap at the upper and lower portions of the flange thereon, and yielding means for backing up said endless chain for forcing the jar cap into contact with the flange turning means.

4. A jar closing machine having in combination, means for turning the flange underneath the ledge on the jar, means for conveying the jar with a cap resting thereon through the machine and with the cap in rolling contact with the flange turning means, said flange turning means including a bar extending throughout the length of the machine, fixed plates associated with said bar at the receiving end thereof, said plates being beveled so as to form with the bar a recess having its lower face inclined for positively starting the inturning of the flange on the cap, and yielding plates cooperating with said bar for finishing the inturning of the flange underneath the ledge and the sealing of the cap on the jar.

5. A jar closing machine having in combination, means for turning the flange underneath the ledge on the jar, means for conveying the jar with a cap resting thereon through the machine and with the cap in rolling contact with the flange turning means, said flange turning means including a bar extending throughout the length of the machine, fixed plates associated with said bar at the receiving end thereof, said plates being beveled so as to form with the bar a recess having its lower face inclined for positively starting the inturning of the flange on the cap, yielding plates cooperating with said bar for finishing the inturning of the flange underneath the ledge and the sealing of the cap on the jar, said inclined face on the plates for starting the inturning of the flange being provided with ribs extending transversely across the same.

6. A jar closing machine having in combination, means for turning the flange underneath the ledge on the jar, means for con-

veying the jar with a cap resting thereon through the machine and with the cap in rolling contact with the flange turning means, said flange turning means including a bar extending throughout the length of the machine, fixed plates associated with said bar at the receiving end thereof, said plates being beveled so as to form with the bar a recess having its lower face inclined for positively starting the inturning of the flange on the cap, and yielding plates cooperating with said bar for finishing the inturning of the flange underneath the ledge and the sealing of the cap on the jar, said yielding plates being independently mounted.

7. A jar closing machine having in combination, means for turning the flange underneath the ledge on the jar, means for conveying the jar with a cap resting thereon through the machine and with the cap in rolling contact with the flange turning means, said flange turning means including a bar extending throughout the length of the machine, fixed plates associated with said bar at the receiving end thereof, said plates being beveled so as to form with the bar a recess having its lower face inclined for positively starting the inturning of the flange on the cap, and yielding plates cooperating with said bar for finishing the inturning of the flange underneath the ledge and the sealing of the cap on the jar, said yielding plates being mounted so that one may yield independent of the others.

8. A jar closing machine having in combination, means for turning the flange underneath the ledge on the jar, means for conveying the jar with a cap resting thereon through the machine and with the cap in rolling contact with the flange turning means, said flange turning means including a bar extending throughout the length of the machine, fixed plates associated with said bar at the receiving end thereof, said plates being beveled so as to form with the bar a recess having its lower face inclined for positively starting the inturning of the flange on the cap, and yielding plates cooperating with said bar for finishing the inturning of the flange underneath the ledge and the sealing of the cap on the jar, said yielding plates being mounted so that one may yield independent of the others, said yielding plate adjacent the fixed beveled plates having its face curved downwardly so as to facilitate the entering of the cap between the yielding plate and the bar with which it is associated.

9. A jar closing machine having in combination, means for turning the flange underneath the ledge on the jar, means for conveying the jar with a cap resting thereon through the machine and with the cap in rolling contact with the flange turning means, said flange turning means including

a bar extending throughout the length of the machine, said bar having a horizontal under face, the extreme inner edge of which is beveled, a series of fixed plates attached to the bar and having their inner faces beveled, said beveled faces being provided with transverse ribs operating to start the inturning of the flange on the cap.

10. A jar closing machine having in combination, means for turning the flange underneath the ledge on the jar, means for conveying the jar with a cap resting thereon through the machine and with the cap in rolling contact with the flange turning means, said flange turning means including a bar extending throughout the length of the machine, said bar having a horizontal under face, the extreme inner edge of which is beveled, a series of fixed plates attached to the bar and having their inner faces beveled, said beveled faces being provided with transverse ribs operating to start the inturning of the flange on the cap, said conveying means including moving means for conveying the jars and caps through the machine in rolling contact with said bar and plates.

11. A jar closing machine having in combination, means for turning the flange underneath the ledge on the jar, means for conveying the jar with a cap resting thereon through the machine and with the cap in rolling contact with the flange turning means, said flange turning means including a bar extending throughout the length of the machine, said bar having a horizontal under face, the extreme inner edge of which is beveled, a series of fixed plates attached to the bar and having their inner faces beveled, said beveled faces being provided with transverse ribs operating to start the inturning of the flange on the cap, said conveying means including a series of plates arranged in pairs and connected to form an endless chain, said plates being spaced and having their inner adjacent edges beveled to facilitate the engagement thereof with the cap on the jar, and yielding means for forcing said traveling chain toward the flange turning means for yieldingly holding the jar cap in contact therewith.

12. A jar closing machine having in combination, means for turning the flange underneath the ledge on the jar, means for conveying the jar with a cap resting thereon through the machine and with the cap in rolling contact with the flange turning means, said flange turning means including a bar extending throughout the length of the machine, said bar having a horizontal under face, the extreme inner edge of which is beveled, a series of fixed plates attached to the bar and having their inner faces beveled, said beveled faces being provided with transverse ribs operating to start the

inturning of the flange on the cap, said conveying means including moving means for conveying the jars and caps through the machine in rolling contact with said bar and plates, and yielding means for forcing said moving means into contact with the cap for yieldingly holding the cap and jar in contact with the flange turning means. 70

13. A jar closing machine having in combination, means for turning the flange of the jar cap underneath the ledge on the jar, means for conveying the jar with the cap resting thereon through the machine with the cap in rolling contact with the flange turning means, said flange turning means including spaced devices between which the flanged edge of the cap passes for positively starting the inturning of the flange on the cap, spaced devices for finishing the inturning of the flange underneath the ledge of the jar, and thus sealing the cap on the jar, said last-named devices being mounted so as to yield relative to each other, and means at the receiving end of the machine for engaging the caps resting loosely on the jars for seating the caps on the jars as they enter the flange turning means. 80

14. A jar closing machine having in combination, means for turning the flange underneath the ledge on the jar, means for conveying the jar with a cap resting thereon through the machine and with the cap in rolling contact with the flange turning means, said flange turning means including a bar extending throughout the length of the machine, fixed plates associated with said bar at the receiving end thereof, said plates being beveled so as to form with the bar a recess having its lower face inclined for positively starting the inturning of the flange on the cap, yielding plates cooperating with said bar for finishing the inturning of the flange underneath the ledge and the sealing of the cap on the jar, and yielding means at the receiving end of the machine for engaging the caps resting loosely on the jars for seating the caps on the jars as they enter the flange turning means. 95 100 105

15. A jar closing machine having in combination, means for turning the flange of the jar cap underneath the ledge on the jar, means for conveying the jar with the cap resting thereon through the machine with the cap in rolling contact with the flange turning means, said flange turning means including spaced devices between which the flanged edge of the cap passes for positively starting the inturning of the flange on the cap, spaced devices for finishing the inturning of the flange underneath the ledge of the jar, and thus sealing the cap on the jar, said last-named devices being mounted so as to yield relative to each other, and a pressure means associated with the conveying means for the jar for engaging 110 115 120 125 130

the caps resting loosely on the jars one after another, for seating the caps on the jars.

16. A jar closing machine having in combination, means for turning the flange of the jar cap underneath the ledge on the jar, means for conveying the jar with the cap resting thereon through the machine with the cap in rolling contact with the flange turning means, said flange turning means including spaced devices between which the flanged edge of the cap passes for positively starting the inturning of the flange on the cap, spaced devices for finishing the inturning of the flange underneath the ledge of the jar, and thus sealing the cap on the jar, said last-named devices being mounted so as to yield relative to each other, a pressure means associated with the conveying means for the jar for engaging the caps resting loosely on the jars one after another, for seating the caps on the jars, said pressure means including a traveling belt, rollers over which said belt travels, a yielding frame for supporting the rollers, and a plate carried by said frame for backing up the traveling belt where the same comes into contact with the caps.

17. A jar closing machine including in combination, a supporting frame, an endless conveyor mounted on said frame, means for driving said endless conveyor, posts rising from said frame at each side of said conveyor, a yoke at each end of the machine connecting said posts, a cross head at each end of the machine adapted to slide on said posts, a threaded rod extending through each yoke and connected to the cross head associated therewith, a threaded sleeve on each rod adapted to rest on the upper face of the yoke with which said rod is associated, means for turning the sleeves for raising and lowering the cross head, and a jar closing and conveying means supported by the cross heads, said closing means including devices for engaging and turning the flange of the cap underneath the ledge on the jar.

18. A jar closing machine including in combination, a supporting frame, an endless conveyor mounted on said frame, means for driving said endless conveyor, posts rising from said frame at each side of said conveyor, a yoke at each end of the machine connecting said posts, a cross head at each end of the machine adapted to slide on said posts, a threaded rod extending through each yoke and connected to the cross head associated therewith, a threaded sleeve on each rod adapted to rest on the upper face of the yoke with which said rod is associated, means for turning the sleeve for raising and lowering the cross head, and a jar closing and conveying means supported by the cross heads, said closing means including devices for engaging and turning the flange of the cap underneath the ledge on the jar, said conveying means including a series of traveling plates connected to form an endless chain, said plates being spaced and positioned so as to engage the flange on the cap and force said cap into contact with the closing means, and springs for normally forcing the traveling plates toward the closing means for yieldingly holding the cap in contact therewith.

19. A jar closing machine including in combination, a supporting frame, an endless conveyor mounted on said frame, means for driving said endless conveyor, posts rising from said frame at each side of said conveyor, a yoke at each end of the machine connecting said posts, a cross head at each end of the machine adapted to slide on said posts, a threaded rod extending through each yoke and connected to the cross head associated therewith, a threaded sleeve on each rod adapted to rest on the upper face of the yoke with which said rod is associated, means for turning the sleeve for raising and lowering the cross head, a jar closing and conveying means supported by the cross heads, said closing means including devices for engaging and turning the flange of the cap underneath the ledge on the jar, said conveying means including a series of traveling plates connected to form an endless chain, said plates being spaced and beveled so as to engage the flange on the cap and force said cap into contact with the closing means.

20. A jar closing machine including in combination, a supporting frame, an endless conveyor mounted on said frame, means for driving said endless conveyor, posts rising from said frame at each side of said conveyor, a yoke at each end of the machine connecting said posts, a cross head at each end of the machine adapted to slide on said posts, a threaded rod extending through each yoke and connected to the cross head associated therewith, a threaded sleeve on each rod adapted to rest on the upper face of the yoke with which said rod is associated, means for turning the sleeve for raising and lowering the cross head, a jar closing and conveying means supported by the cross heads, said closing means including devices for engaging and turning the flange of the cap underneath the ledge on the jar, said conveying means including a series of traveling plates connected to form an endless chain, said plates being spaced and beveled so as to engage the flange on the cap and force said cap into contact with the closing means, and springs for normally forcing the traveling plates toward the closing means for yieldingly holding the cap in contact therewith.

21. A jar closing machine including in combination, a supporting frame, an endless conveyor mounted on said frame, means for driving said endless conveyor, posts rising from said frame at each side of said conveyor, a yoke at each end of the machine connecting said posts, a cross head at each end of the machine adapted to slide on said posts, a threaded rod extending through each yoke and connected to the cross head associated therewith, a threaded sleeve on each rod adapted to rest on the upper face of the yoke with which said rod is associated, means for turning the sleeve for raising and lowering the cross head, and a jar closing and conveying means supported by the cross heads, said closing means including devices for engaging and turning the flange of the cap underneath the ledge on the jar, said conveying means including a series of traveling plates connected to form an endless chain, said plates being spaced and beveled so as to engage the flange on the cap and force said cap into contact with the closing means, and springs for normally forcing the traveling plates toward the closing means for yieldingly holding the cap in contact therewith.

22. A jar closing machine including in combination, a supporting frame, an endless conveyor mounted on said frame, means for driving said endless conveyor, posts rising from said frame at each side of said conveyor, a yoke at each end of the machine connecting said posts, a cross head at each end of the machine adapted to slide on said posts, a threaded rod extending through each yoke and connected to the cross head associated therewith, a threaded sleeve on each rod adapted to rest on the upper face of the yoke with which said rod is associated, means for turning the sleeve for raising and lowering the cross head, a jar closing and conveying means supported by the cross heads, said closing means including devices for engaging and turning the flange of the cap underneath the ledge on the jar, said conveying means including a series of traveling plates connected to form an endless chain, said plates being spaced and positioned so as to engage the flange on the cap and force said cap into contact with the closing means, and springs for normally forcing the traveling plates toward the closing means for yieldingly holding the cap in contact therewith, said closing means including a series of plates adapted to yield vertically for finishing the

- 5 inturning of the flange whereby the means for inturning the flange and for holding the caps in rolled contact with said closing means, both may yield to accommodate varying thicknesses in the glass and the metal.
- 10 21. A jar closing machine including in combination, a supporting frame, an endless conveyor mounted on said frame, means for driving said endless conveyor, posts rising from said frame at each side of said conveyor, a yoke at each end of the machine connecting said posts, a cross head at each end of the machine adapted to slide on said posts, a threaded rod extending through each yoke and connected to the cross head associated therewith, a threaded sleeve on each rod adapted to rest on the upper face of the yoke with which said rod is associated, means for turning the sleeve for raising and lowering the cross head, a jar closing and conveying means supported by the cross heads, said closing means including devices for engaging and turning the flange of the cap underneath the ledge on the jar, said conveying means including a series of traveling plates connected to form an endless chain, said plates being spaced and positioned so as to engage the flange on the cap and force said cap into contact with the closing means, and springs for normally forcing the traveling plates toward the closing means for yieldingly holding the cap in contact therewith, said closing means including a series of plates adapted to yield vertically for finishing the inturning of the flange whereby the means for inturning the flange and for holding the caps in rolled contact with said closing means both may yield to accommodate varying thicknesses in the glass and the metal, said closing means and conveying means being constructed so as to lift the jar from the conveyor belt and support the same by a ledge thereon during the turning of the cap underneath said ledge, means for adjusting the closing means toward and from the conveying means for setting the machine for different sized caps, and means connected to the sleeves and to each other for raising and lowering the cross heads for different heights of jars.
- 15 22. A jar closing machine including in combination, a supporting frame, an endless conveyor mounted on said frame, means for driving said endless conveyor, posts rising from said frame at each side of said conveyor, a yoke at each end of the machine connecting said posts, a cross head at each end of the machine adapted to slide on said posts, a threaded rod extending through each yoke and connected to the cross head associated therewith, a threaded sleeve on each rod adapted to rest on the upper face of the yoke with which said rod is associated, means for turning the sleeve for raising and lowering the cross head, a jar closing and conveying means supported by the cross heads, said closing means including devices for engaging and turning the flange of the cap underneath the ledge of the jar, said closing means and conveying means being constructed so as to lift the jar from the conveyor belt and support the same by a ledge thereon during the turning of the cap underneath said ledge, means for adjusting the closing means toward and from the conveying means for setting the machine for different sized caps, and means connected to the sleeves where the same are simultaneously operated for raising and lowering the cross heads for different heights of jars, and pressure means at the entrance end of the machine supported by said cross heads and movable up and down therewith, said pressure means operating to engage the caps loosely resting on the jars on the conveyor belt for seating the caps before they enter the closing means.
- 20 23. A jar closing machine including in combination, a supporting frame, an endless conveyor mounted on said frame, means for driving said endless conveyor, posts rising from said frame at each side of said conveyor, a yoke at each end of the machine connecting said posts, a cross head at each end of the machine adapted to slide on said posts, a threaded rod extending through each yoke and connected to the cross head associated therewith, a threaded sleeve on each rod adapted to rest on the upper face of the yoke with which said rod is associated, means for turning the sleeve for raising and lowering the cross head, a jar closing and conveying means supported by the cross heads, said closing means including devices for engaging and turning the flange of the cap underneath the ledge of the jar, said closing means and conveying means being constructed so as to lift the jar from the conveyor belt and support the same by a ledge thereon during the turning of the cap underneath said ledge, means for adjusting the closing means toward and from the conveying means for setting the machine for different sized caps, and means connected to the sleeves where the same are simultaneously operated for raising and lowering the cross heads for different heights of jars, and pressure means at the entrance end of the machine supported by said cross heads and movable up and down therewith, said pressure means operating to engage the caps loosely resting on the jars on the conveyor belt for seating the caps before they enter the closing means.
- 25 24. A jar closing machine including in combination, a supporting frame, an endless conveyor mounted on said frame, means for driving said endless conveyor, posts rising from said frame at each side of said conveyor, a yoke at each end of the machine connecting said posts, a cross head at each end of the machine adapted to slide on said posts, a threaded rod extending through each yoke and connected to the cross head associated therewith, a threaded sleeve on each rod adapted to rest on the upper face of the yoke with which said rod is associated, means for turning the sleeve for raising and lowering the cross head, a jar closing and conveying means supported by the cross heads, said closing means including devices for engaging and turning the flange of the cap underneath the ledge on the jar, said conveying means including a series of traveling plates connected to form an endless

- from said frame at each side of said conveyor, a yoke at each end of the machine connecting said posts, a cross head at each end of the machine adapted to slide on said 5 posts, a threaded rod extending through the yoke and connected to the cross head for raising and lowering the same, a threaded sleeve on said rod, said sleeve resting on the upper face of the yoke, means for turning 10 the sleeve for raising and lowering the cross head, a jar closing and conveying means supported by the cross heads, pressure means at the entrance end of the machine supported by said cross heads and movable up and 15 down therewith, said pressure means operating to engage the caps loosely resting on the jars on the conveyor belt for seating the caps before they enter the closing means, said pressure seating means including an 20 endless traveling belt, rollers over which said belt travels, a frame pivotally supported by the cross head on which said rollers are mounted whereby said rollers may move up and down, a spring for normally forcing 25 said frame in a downward direction to yieldingly force the belt into contact with the caps, and means for limiting the downward movement of said frame.

25. A jar closing machine including in combination, a supporting frame, an endless conveyor mounted on said frame, means for driving said endless conveyor, posts rising from said frame at each side of said conveyor, a yoke at each end of the machine 30 connecting said posts, a cross head at each end of the machine adapted to slide on said posts, a threaded rod extending through the yoke and connected to the cross head for raising and lowering the same, a threaded 35 sleeve on said rod, said sleeve resting on the upper face of the yoke, means for turning the sleeve for raising and lowering the cross head, a jar closing and conveying means supported by the cross heads, pressure means 40 at the entrance end of the machine supported by said cross heads and movable up and down therewith, said pressure means operating to engage the caps loosely resting on the jars on the conveyor belt for seating the caps before they enter the closing means, 45 said pressure seating means including an endless traveling belt, rollers over which said belt travels, a frame pivotally supported by the cross head on which said rollers are mounted whereby said rollers may move up and 50 down, a spring for normally forcing said frame in a downward direction to yieldingly force the belt into contact with the caps, means for limiting the downward movement of said frame, and a plate carried by said frame for backing up the belt where it engages the caps so as to form a 55 rigid surface over which the moving belt travels.

60 26. A jar closing machine including in combination, a supporting frame, an endless conveyor extending the length of said frame, a supporting structure spaced above said conveyor belt and carried by said supporting frame, a bar carried by said supporting structure and extending lengthwise of the machine parallel with the travel of the belt, a series of plates associated with said bar and fixed thereto, said plates forming with said bar a recess to receive and start the 65 inturning of the flange on the cap, a series of plates associated with said bar and independently yielding relative thereto for engaging the flange and finishing the inturning of the same underneath the ledge on the jar, a conveying means carried by said supporting structure for engaging the other side of the jar cap for yieldingly pressing the jar and cap into contact with said plates, said plates and conveying means being positioned relative to the endless conveyor so as to lift the jar from the conveying belt and support the same by the ledge of the mouth of the jar during the closing of the 70 cap thereon.

27. A jar closing machine including in combination a supporting frame, an endless conveyor extending the length of said frame, a supporting structure spaced above said conveyor belt and carried by said supporting frame, a bar carried by said supporting structure and extending lengthwise of the machine parallel with the travel of the belt, a series of plates associated with said bar and fixed thereto, said plates forming with said bar a recess to receive and start the 75 inturning of the flange on the cap, a series of plates associated with said bar and independently yielding relative thereto for engaging the flange and finishing the inturning of the same underneath the ledge on the jar, a conveying means carried by said supporting structure for engaging the other side of the jar cap for yieldingly pressing the jar and cap into contact with said plates, said plates and conveying means being positioned relative to the endless conveyor so as to lift the jar from the conveying belt and support the same by the ledge of the mouth of the jar during the closing of the 80 cap thereon.

28. A jar closing machine including in combination a supporting frame, an endless conveyor extending the length of said frame, a supporting structure spaced above said conveyor belt and carried by said supporting frame, a bar carried by said supporting structure and extending lengthwise of the machine parallel with the travel of the belt, a series of plates associated with said bar and fixed thereto, said plates forming with said bar a recess to receive and start the 85 inturning of the flange on the cap, a series of plates associated with said bar and independently yielding relative thereto for engaging the flange and finishing the inturning of the same underneath the ledge on the jar, a conveying means carried by said supporting structure for engaging the other side of the jar cap for yieldingly pressing the jar and cap into contact with said plates, said plates and conveying means being positioned relative to the endless conveyor so as to lift the jar from the conveying belt and support the same by the ledge of the mouth of the jar during the closing of the 90 cap thereon.

29. A jar closing machine including in combination a supporting frame, an endless conveyor extending the length of said frame, a supporting structure spaced above said conveyor belt and carried by said supporting frame, a bar carried by said supporting structure and extending lengthwise of the machine parallel with the travel of the belt, a series of plates associated with said bar and fixed thereto, said plates forming with said bar a recess to receive and start the 95 inturning of the flange on the cap, a series of plates associated with said bar and independently yielding relative thereto for engaging the flange and finishing the inturning of the same underneath the ledge on the jar, a conveying means carried by said supporting structure for engaging the other side of the jar cap for yieldingly pressing the jar and cap into contact with said plates, said plates and conveying means being positioned relative to the endless conveyor so as to lift the jar from the conveying belt and support the same by the ledge of the mouth of the jar during the closing of the 100 cap thereon.

30. A jar closing machine including in combination a supporting frame, an endless conveyor extending the length of said frame, a supporting structure spaced above said conveyor belt and carried by said supporting frame, a bar carried by said supporting structure and extending lengthwise of the machine parallel with the travel of the belt, a series of plates associated with said bar and fixed thereto, said plates forming with said bar a recess to receive and start the 105 inturning of the flange on the cap, a series of plates associated with said bar and independently yielding relative thereto for engaging the flange and finishing the inturning of the same underneath the ledge on the jar, a conveying means carried by said supporting structure for engaging the other side of the jar cap for yieldingly pressing the jar and cap into contact with said plates, said plates and conveying means being positioned relative to the endless conveyor so as to lift the jar from the conveying belt and support the same by the ledge of the mouth of the jar during the closing of the 110 cap thereon.

31. A jar closing machine including in combination a supporting frame, an endless conveyor extending the length of said frame, a supporting structure spaced above said conveyor belt and carried by said supporting frame, a bar carried by said supporting structure and extending lengthwise of the machine parallel with the travel of the belt, a series of plates associated with said bar and fixed thereto, said plates forming with said bar a recess to receive and start the 115 inturning of the flange on the cap, a series of plates associated with said bar and independently yielding relative thereto for engaging the flange and finishing the inturning of the same underneath the ledge on the jar, a conveying means carried by said supporting structure for engaging the other side of the jar cap for yieldingly pressing the jar and cap into contact with said plates, said plates and conveying means being positioned relative to the endless conveyor so as to lift the jar from the conveying belt and support the same by the ledge of the mouth of the jar during the closing of the 120 cap thereon.

32. A jar closing machine including in combination a supporting frame, an endless conveyor extending the length of said frame, a supporting structure spaced above said conveyor belt and carried by said supporting frame, a bar carried by said supporting structure and extending lengthwise of the machine parallel with the travel of the belt, a series of plates associated with said bar and fixed thereto, said plates forming with said bar a recess to receive and start the 125 inturning of the flange on the cap, a series of plates associated with said bar and independently yielding relative thereto for engaging the flange and finishing the inturning of the same underneath the ledge on the jar, a conveying means carried by said supporting structure for engaging the other side of the jar cap for yieldingly pressing the jar and cap into contact with said plates, said plates and conveying means being positioned relative to the endless conveyor so as to lift the jar from the conveying belt and support the same by the ledge of the mouth of the jar during the closing of the 130 cap thereon.

turning of the flange on the cap, a series of plates associated with said bar and independently yielding relative thereto for engaging the flange and finishing the inturning of the same underneath the ledge on the jar, a conveying means carried by said supporting structure for engaging the other side of the jar cap for yieldingly pressing the jar and cap into contact with said plates, 5 said plates and conveying means being positioned relative to the endless conveyor so as to lift the jar from the conveying belt and support the same by the ledge of the mouth of the jar during the closing of the cap 10 thereon, and a pressure means carried by said supporting structure for engaging and seating the caps on the jars before they enter the closing means, said yielding plates being constructed so as to lower the jar on to 15 the conveyor belt after the cap has been closed on the jar.

29. A jar closing machine including in combination, a supporting frame, an endless conveyor extending the length of said frame, 25 a supporting structure spaced above said conveyor belt and carried by said supporting frame, a bar carried by said supporting structure and extending lengthwise of the machine parallel with the travel of the belt, 30 a series of plates associated with said bar and fixed thereto, said plates forming with said bar a recess to receive and start the inturning of the flange on the cap, a series 35 of plates associated with said bar and independently yielding relative thereto for engaging the flange and finishing the inturning of the same underneath the ledge on the jar, a conveying means carried by said supporting structure for engaging the other 40 side of the jar cap for yieldingly pressing the jar and cap into contact with said plates, said plates and conveying means being positioned relative to the endless conveyor so as to lift the jar from the conveying belt and support the same by the ledge of the mouth of the jar during the closing of the cap 45 thereon, a pressure means for engaging the caps for seating the same on the jars before they are engaged by the closing plates, said pressure means including a traveling belt, a yielding plate over which said belt travels, a spring for forcing said plate in a downward direction, and means for limiting the downward movement of said plate.

30. A jar closing machine including in combination, a supporting frame, an endless conveyor extending the length of said frame, 50 a supporting structure spaced above said conveyor belt and carried by said supporting frame, a bar carried by said supporting structure and extending lengthwise of the machine parallel with the travel of the belt, 55 a series of plates associated with said bar and fixed thereto, said plates forming with said bar a recess to receive and start the inturning of the flange on the cap, a series 60 of plates associated with said bar and independently yielding relative thereto for engaging the flange and finishing the inturning of the same underneath the ledge on the jar, a conveying means carried by said supporting structure for engaging the other 65 side of the jar cap for yieldingly pressing the jar and cap into contact with said plates, said plates and conveying means being positioned relative to the endless conveyor so as to lift the jar from the conveying belt and support the same by the ledge of the mouth of the jar during the closing of the cap 70 thereon, a pressure means for engaging the caps for seating the same on the jars before they are engaged by the closing plates, said pressure means including a traveling belt, a yielding plate over which said belt travels, a spring for forcing said plate in a downward direction, and means for limiting the downward movement of said plate, 75 said yielding plate at the delivery end of the machine being beveled off on its upper face so that the jar passing off the end of the 80 same will move down onto the conveyor belt.

In testimony whereof, I affix my signature.

THOMAS L. TALIAFERRO.
